UNITED STATES PATENT OFFICE.

HARRY W. NEAL, OF INDIANAPOLIS, INDIANA, ASSIGNOR TO HALL-NEAL FURNACE COMPANY, OF INDIANAPOLIS, INDIANA, A CORPORATION OF INDIANA.

DOMESTIC HEATING FURNACE.

Application filed July 31, 1922. Serial No. 578,671.

To all whom it may concern:

Be it known that I, HARRY W. NEAL, a citizen of the United States, residing at Indianapolis, in the county of Marion and 5 State of Indiana, have invented certain new and useful Improvements in Domestic Heating Furnaces, of which the following is a specification.

This invention relates to a method of 10 constructing and manufacturing hot air furnaces for domestic heating purposes.

One of the objects of the invention consists in the provision of a method whereby hot air furnaces fabricated and manufactured in accordance with my improved method results substantially in an integral 15 unitary structure wherein expansion and contraction is uniformly distributed so as to prevent undue and premature injury of the 20 parts.

A further object of the invention consists in the provision of a certain improved method of fabricating and constructing hot air heating furnaces wherein the heat radiating capacity is greatly increased, and the 25 cost of construction materially reduced.

I accomplish the above objects of the invention, and such others as may appear from a perusal of the following description and 30 claims relating to such method of fabricating and constructing, as exemplified in a preferred composite structure shown in accompanying drawings, which form a part of this application, in which—

35 Figure 1 is a partial side elevation and a partial longitudinal sectional view of a domestic heating furnace constructed in accordance with my improved method. Fig. 2 is a top or plan view of the furnace, the 40 outer casing being cut away on the plane 2—2 in Fig. 1. Fig. 3 is a fragmentary detail vertical section of the forward portion of the furnace, in which the outer casing is omitted. Fig. 4 is a transverse view 45 looking towards the front end of the furnace, on the plane 4—4 in Fig. 3. Fig. 5 is a horizontal sectional view of the furnace, on the plane 5—5 in Fig. 1. Fig. 6 is a fragmentary detail sectional view, on an enlarged 50 scale, showing more clearly the joint for securing the division wall with the furnace walls. Fig. 7 is a fragmentary detail view in side elevation of the rear portion of the furnace. Fig. 8 is a transverse sectional 55 view looking towards the rear end of the

furnace, on the plane 8—8 in Fig. 1, the outer casing in this figure being omitted. Fig. 9 is an elevation of the rear end of the furnace. Fig. 10 is a perspective view of a pair of crimped members which conjointly 60 form one of the integral sections of the unitary furnace structure. Fig. 11 is a plan view of a furnace-member blank as it appears when cut from the raw stock.

65 Referring to the drawings, I have illustrated a composite heating furnace structure fabricated and constructed in accordance with my improved method, which consists in stamping or cutting from the raw material stock a number of individual blanks 15, 70 as illustrated in Fig. 11, which may at the same operation, or subsequent thereto, be bent along the dotted line 16, 17, 18, 19 and 20 into an angular member 25 as illustrated in Fig. 10. It will be observed that all the 75 members 25 are bent in a like manner to promote uniformity in contour, and thereby require but a single cutting die. These members 25 may then be arranged in pairs and in reverse positions, as shown in Fig. 10, 80 and when properly united each pair of members forms a section of the furnace. When two of the members 25 are placed in a reversed order their meeting edges are brought together, alined, and then welded together 85 along the dotted lines A—B in Figs. 4 and 8 to form integral sections of the subsequently unitary furnace structure. Each of the furnace sections, composed of two of the united members 25, has the side edges bent outwardly into the right angle flanges 25^a which 90 not only provide large bearing surfaces for the attachment of the succeeding sections, but in addition increase the heat radiating surface area of the furnace, and, furthermore, the flanges serve the purpose of accelerating the action of extraction of heat 95 from the members 25 constituting the walls of the furnace. The number of the aforesaid described assembled furnace sections is 100 determined by calculating the number of cubic feet of air space to be heated in a given house. After the desired number of the furnace sections are assembled together with the flat faces of the flanges 25^a abutting one another, as shown in Fig. 5, each pair of contacting flanges is securely welded 105 together to form the unitary integral furnace structure. The open remaining ends of the unitary furnace structure are closed by 110

means of the end-members 30 and 31, each of these members being welded to the broad face of the adjacent section 25. The front end member 30 is provided with the usual 5 fuel opening 33 and the ash-pit opening 34, and the rear end member 31 is provided with the usual smoke outlet openings 35 and 36, and a clean-out opening 37. In constructing the end members 30 and 31, I introduce the 10 novel arrangement which consists in forming those members on arcs in cross section so that these members will more easily respond to the action of expansion and contraction, thereby correspondingly reducing the liability 15 of such action affecting the welded joints formed between the end members and the furnace sections 25.

In my improved method of constructing hot air heating furnaces, I also provide 20 means for the attachment of the usual baffle-plate or transverse division wall 40 without the use of bolts, screws or rivets, and thereby remove the liability of stresses being localized in the walls of the furnace which 25 are incident to the action of expansion and contraction of division wall 40. As shown in Fig. 6, the meeting faces of flanges 25^a of the abutting furnace sections, where I desire to mount division wall 40, are given a 30 slight reverse bending, as at 25^b, to provide grooves or channels 41 which are of such width as to conveniently receive the marginal edge-portion of division wall 40. Division wall 40, similarly to the end-members 35 30 and 31, is bent on an arc so that it may readily respond to the action of expansion and contraction of the unitary furnace structure. Division wall 40 is provided with the smoke opening 43 through which 40 the smoke passes from the combustion chamber 44 from which the smoke may pass directly into the outlet pipe 45, or it may be deflected into chamber 46 back of division wall 40 and effect an escape through open-

ing 36, thence upwardly through the vertical pipe 47 and back to the pipe 45, depending upon the position occupied by damper 48.

With the preceding disclosure of one of the preferred embodiments of the invention constructed in accordance with my improved method as a guide, it will be easy for those skilled in this art to design other forms of unitary furnace structures—to meet particular requirements of use—which will present all of the functional and result attaining characteristics and advantages of my improved method.

I claim:

1. A furnace body comprising a plurality of duplicate endless sections each section having parallel flanges at opposite sides welded to contacting flanges of adjacent sections said flanges including a pair of stepped flanges, and a baffle plate of greater diameter than the inner diameter of the furnace said baffle plate having its outer edges extending between the stepped flanges, substantially as set forth.

2. A furnace body structure comprising a plurality of duplicate endless sections each section consisting of a pair of identical members each member having flanges extending at right angles to the main portion thereof said members also having their ends extending inward to provide upper and lower walls said pair of members in each section being oppositely arranged and welded together at the meeting edges of the said upper and lower walls and adjacent sections having their contacting flanges welded together, substantially as set forth.

In witness whereof, I have hereunto set my hand and seal at Indianapolis, Indiana, this 29th day of July, A. D., one thousand eight hundred and twenty-two.

HARRY W. NEAL. [L. S.]
